(57) **CLAIM**

I claim the ornamental design for a monitor for analyte detection, as shown and described.

DESCRIPTION

FIG. 1 is an isometric view of a monitor for analyte detection showing my new design with the abrader portion removed for clarity of illustration;

FIG. 2 is a front elevation view thereof;

FIG. 3 is a side elevation view thereof;

FIG. 4 is a back elevation view thereof;

FIG. 5 is the opposite side elevation view thereof;

FIG. 6 is a top elevation view thereof;

FIG. 7 is a bottom elevation view thereof;

FIG. 8 is a bottom isometric view thereof;

FIG. 9 is an isometric view of a monitor for analyte detection shown in FIG. 1 with the abrader portion attached;

FIG. 10 is a front elevation view thereof;

FIG. 11 is a side elevation view thereof;

FIG. 12 is a back elevation view thereof;

FIG. 13 is the opposite side elevation view thereof;

FIG. 14 is a top elevation view thereof;

FIG. 15 is a bottom elevation view thereof; and,

FIG. 16 is a bottom isometric view thereof.

The broken lines in the drawings are for purpose of illustrating portions of the monitor for analyte detection, which form no part of the claimed design.
